UNITED STATES PATENT OFFICE.

CHARLES J. WASHMAN, OF TERRELL, TEXAS.

DESIGN FOR A TOILET-CABINET.

43,172.

Specification for Design.

Patented Oct. 15, 1912.

Application filed May 14, 1912. Serial No. 697,337. Term of patent 7 years.

To all whom it may concern:

Be it known that I, CHARLES J. WASHMAN, a citizen of the United States, residing at Terrell, Kaufman county, State of Texas, have invented a new, original, and ornamental Design for Toilet-Cabinets, of which the following is a specification, reference being had to the accompanying drawing, forming part thereof.

The figure is a perspective view of the toilet cabinet, showing my new design.

I claim:

The ornamental design for a toilet cabinet as shown.

CHARLES J. WASHMAN.

Witnesses:

W. P. DUMAS,
ED. R. BONIFACE.
